[57] CLAIM

The ornamental design for a remote security monitor system, as shown and described.

DESCRIPTION

FIG. 1 is a perspective view of a remote security monitor system showing our new design, with the wires broken away to indicate indeterminate length;

FIG. 2 is a front view of the monitor portion thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a front view of the cellular phone portion thereof;

FIG. 9 is a rear view thereof;

FIG. 10 is a left view thereof; and the right view is a mirror image thereof;

FIG. 11 is a top view thereof; and,

FIG. 12 is a bottom view thereof.
